United States Patent Office.

WILLIAM F. PARKER, OF ANDOVER, MASSACHUSETTS.

Letters Patent No. 64,357, dated April 30, 1867.

IMPROVED DRILLING MACHINE.

The Schedule referred to in these Letters Patent and making part of the same.

Be it known that I, WILLIAM F. PARKER, of Andover, in the county of Essex, and Commonwealth of Massachusetts, have invented a new and useful Machine for Drilling or Boring; and I do hereby declare that the following is a full, clear, and exact description of the construction and operation of the same, reference being had to the annexed drawings, making a part of this specification, in which—

Figure 1 is a side view of machine when used as a Scotch drill.

Figure 2 represents an end view of machine when used as a Scotch drill.

Figure 3 represents a side view of machine when used as a ratchet drill.

Figure 4 is an end view of machine when used as a ratchet drill.

Figure 5 represents an interior side view of machine.

Figure 6 represents the feeding part of the machine.

Figure 7 represents a vertical view of the feeding part of the machine.

A is the shaft to which the power is applied to move the machine, which is done by means of the crank B which passes through the shaft A and is fastened by the screw c in the shaft A at any point desired, so as to give the crank a longer or shorter leverage as may be desirable. The shaft A passes through the frame of the machine D and is fastened in the bevelled cog-wheel E, and this cog-wheel E works in a similar cog-wheel on the vertical drilling-shaft F, and said cog-wheel is fastened to the drilling-shaft by a key, the key being made smaller than the groove G in the drilling-shaft, so that the drilling-shaft F may slip up or down in the cog-wheel when the machine is used. In the lower end of the drilling-shaft F is inserted the drill, as see H. The upper end of the drilling-shaft F is a hollow cylinder, with threads cut on the interior surface of said cylinder to receive the threads of the screw I; this screw may be longer or shorter according to the depth of the holes to be bored or drilled by the machine. The screw I is made as other screws, with this exception, that in the screw I a slot or groove is made the whole length of it to receive the knob on the interior surface of the ratchet-wheel K. Upon the upper end of the screw I is a head with a point at the top, which moves in a cavity in an iron plate, q, and turns as on a pivot. On this screw I there is a ratchet-wheel, K, having the screw for its axle (there being no threads cut on the interior surface of the ratchet-wheel) having a knob on its interior surface which moves freely up and down in a slot or groove in the screw I, above described, so that when the ratchet-wheel K turns the screw I must also turn. Just below the ratchet-wheel K is a cam-wheel, M, the diameter of which is a little larger than the diameter of the ratchet K, and is fixed firmly by a screw to the top of the drilling-shaft F, and serves to keep the pawl N from coming in contact with the teeth of the ratchet-wheel K except at one place, O, fig. 7, where the cam M is cut away so that the pawl may come in contact with the ratchet-wheel teeth. This opening O (see fig. 7) may be closed more or less by the slide P, which is fastened to the drilling-shaft F, and which may be moved along in its slot so as to let more or less of the teeth of the ratchet K come in contact with the pawl N during each revolution of the drilling-shaft according to the desire to feed faster or slower. N is a pawl which is pressed against the cam M and ratchet-wheel K by spiral springs R R; said springs are set in the frame D of the machine, and the pawl is kept in position by an arm of the pawl passing through the frame of the machine. This pawl N is prevented from touching the ratchet-wheel teeth by the cam M except at the space O, where the pawl comes in contact with one or more teeth of the ratchet-wheel K. The ratchet-wheel K and the pawl N are to turn the screw I, and thus force down the drill into the article to be bored or drilled, but it would feed too fast, therefore the cam M is put on for the purpose of keeping the pawl from the ratchet-wheel the larger part of each revolution. Enough of the cam M is cut away to allow enough of the teeth of the ratchet to come in contact with the pawl N to cause the machine to feed as fast as the machine could drill or bore in any metal, and to regulate the feed so as to drill any metal, hard or soft, the slide P is made to close part of the opening O in the cam M, and so cause the machine to feed fast or slow, as desired. It will be seen that the fewer number of teeth of the ratchet-wheel which are exposed to the pawl the slower the machine will feed. The machine is fastened to a bench or table when used as a Scotch drill by means of a hand vise, the jaws of which, S S, fig. 1, grasp the bench T and are made fast by the screws U U, one of which is longer than the other, and passes up through the slot in the arm V and is made tight by the nut W pressing the arm V down on to a shoulder on the screw U. The arm V having a slot the screw may be moved along in it at pleasure so as to bore or drill a series of holes as may be desired. The arm V

is firmly attached to the machine by a screw at X. When the machine is used as a ratchet-drill, I simply take off the top piece of the frame Q of the machine, and rest the top end of the screw I against one side of say a door-way and bore into the other side of the door-way, but if the door-way is too wide for the machine a block may be set against the end of the screw I, and the machine is in position to bore or drill.

The machine being in position as described, when used either as a Scotch drill or a ratchet-drill, the method is the same in both cases simply by turning the crank B, which causes the bevel-gears E E to move or turn, and with them the drilling-shaft F with the cam-wheel M and slide P, they both being fastened to the drilling-shaft, and as the shaft turns the pawl N slides around on the cam M until it comes to the part of the disk O which is cut away, when the pawl N comes in contact with the teeth of the ratchet-wheel K, causing it to turn and with it the screw I, thus forcing by the screw the drill downward into the article to be bored, but soon the pawl strikes the other side of the opening O in the cam and is forced back, and passes along on the disk of the cam until it comes to the opening, when the machine will feed as before.

1. I claim the combination of the pawl N with the ratchet-wheel K, the cam M, and the slide P, for the purposes herein set forth and described.

2. In combination with the subject-matter of the foregoing clause, and with the supporting frame, I claim the top piece Q, arranged as described.

WILLIAM F. PARKER. [L.S.]
